George F. Quayle, Philadelphia, Pa., assignor to The Yale and Towne Manufacturing Company, Stamford, Conn., a corporation of Connecticut

Filed June 3, 1958, Ser. No. 739,582

5 Claims. (Cl. 214—652)

This invention relates to industrial trucks, and more particularly to that class of industrial trucks in which the load lifting member is an outwardly extending arm or ram that is inserted into an opening in the load.

Constructions of this class are known to those skilled in the art, and much effort has been expended in the development of various operating constructions. Nevertheless, I have conceived a completely new and different combination of parts that yields results heretofore unattainable by trucks of known construction. Thus, as a result of my concept, I am able to lift a coil of tinplate, for example, the central cylindrical opening of which is horizontal, bring a pallet into juxtaposed relation with one of the flat sides of the coil, rotate the coil and pallet together so that the central opening of the coil is vertical, and deposit the palletized coil on any flat surface.

In essence, my invention resides in the utilization of an up-ender rotatably carried by an industrial truck. A coil lifting ram and a pallet carrier are mounted for rotation with the up-ender and also for linear movement relatively to the up-ender. The up-ender is supported on a carriage that is, in turn, mounted for vertical movement on a pair of uprights carried by the main frame of the truck.

As an important feature of my invention, the ram is so mounted relatively to the up-ender that it is also rotatable in an axis that is offset and angular relatively to the line of direction in which the ram moves linearly relatively to the up-ender, this axis of rotation being also angular to the axis of rotation of the up-ender itself.

As another feature of the invention, I equip the up-ender with guide members and I mount the ram on a ram carrier that engages these guide members for linear movement relatively to the up-ender in any of its rotated positions.

As a further feature of the invention, I arrange the ram carrier to support a head for linear movement in a line of direction angular to the line of direction of linear movement of the ram carrier itself relatively to the up-ender. The coil engaging ram is mounted on this head for movement therewith.

As another important feature of the invention, the pallet carrier is also mounted on the guide members for linear movement relatively to the up-ender in any of its rotated positions. The line of direction of linear movement of the pallet carrier relatively to the up-ender is parallel to the line of direction of linear movement of the ram carrier relatively to the up-ender. In this way, a coil carried by the ram and a pallet carried by the pallet carrier may be brought into juxtaposition for deposition with the pallet supporting the coil.

2

I have thus outlined rather broadly the more important features of my invention in order that the detailed description thereof that follows may be better understood, and in order that my contribution to the art may be better appreciated. There are, of course additional features of my invention that will be described hereinafter and which will form the subject of the claims appended hereto. Those skilled in the art will appreciate that the conception on which my disclosure is based may readily be utilized as a basis for the designing of other structures for carrying out the several purposes of my invention. It is important, therefore, that the claims be regarded as including such equivalent constructions as do not depart from the spirit and scope of my invention, in order to prevent the appropriation of my invention by those skilled in the art.

An illustrative embodiment of the invention has been chosen for purposes of illustration and description, and is shown in the accompanying drawing forming a part of the specification.

In the drawing:

Fig. 1 is a side elevational view of a coil handling truck approaching a stack of pallets;

Fig. 2 is a fragmentary side elevational view of the truck carrying a pallet that has been lifted and rotated ninety degrees;

Fig. 3 is similar to Fig. 2, but shows the ram inserted into the central cylindrical opening or eye of a coil to be lifted;

Fig. 4 is similar to Figs. 2 and 3, but shows the ram and coil rotated ninety degrees about a vertical axis so that a flat side of the coil is presented to a flat surface of the pallet;

Fig. 5 is a front elevational view showing the pallet and coil in juxtaposed relation;

Fig. 6 is similar to Fig. 5, but shows the pallet and coil up-ended;

Fig. 7 is similar to Fig. 6, but illustrates the ram withdrawn from the eye of the coil;

Fig. 8 shows the ram shifted centrally of the truck;

Fig. 9 shows the pallet carrier depositing the pallet with the up-ended coil on a flat surface;

Fig. 10 is a top plan view of a portion of a truck carrying the coil handling apparatus of the present invention, parts of the apparatus being broken away for clarity;

Fig. 11 is a sectional view taken along the line 11—11 of Fig. 10 and showing the ram and pallet carrier in alternate positions in broken lines;

Fig. 12 is a rear elevational view taken along the line 12—12 of Fig. 11;

Fig. 13 is a sectional view taken along the line 13—13 of Fig. 12; and

Fig. 14 is a sectional view taken along the line 14—14 of Fig. 11.

Referring to the drawing, and, more particularly to Figs. 1, 10, 11 and 12, there is shown an industrial truck 10 having a pair of front wheels 11, a rear wheel 12, and a main frame 14 upon which is provided an operator's station 15. The main frame 14 supports a pair of vertical, channelled uprights 16, the channels of which are disposed to face outwardly.

A carriage 17 is arranged just forward of the uprights 16, and, in order that this carriage may be guided by the uprights in vertical movement, rearwardly extending

brackets 19 are secured to the carriage and extend across the channels in the uprights 17. A pair of rollers 20 is rotatably mounted on each bracket 19 and is confined within the channel of the adjacent upright to guide the carriage in vertical movement relatively to the uprights. To effect vertical movement of the carriage 17, I provide a pair of hydraulic rams 21 the cylinders of which are pivotally connected by brackets 22 and pins 24 to a cross-piece 25 secured to the bottoms of the uprights 16. The piston rods 26 of these rams are pivotally connected by similar brackets 22' and pins 24' to a horizontal plate 27 extending rearwardly of the carriage.

An up-ender 29 is supported by the carriage for rotary movement relatively thereto, and includes a plate 30 only slightly spaced forwardly of the carriage 17. An annular wear strip 31 is secured by screws to the carriage 17 and serves as a spacer between the carriage and the plate 30. The annular space between the shaft 32 and the wear strip 31 is preferably filled with a lubricating grease.

As best shown in Figs. 10, 12, and 13, a shaft 32 is mounted in a bearing member 34 secured to the carriage 17 and extending rearwardly thereof to enclose suitable roller bearings 35 that are angulated to rotatably support the shaft against longitudinal movement. The shaft 32 extends forwardly through the up-ender plate 30, to which it is welded, and this connection is reinforced by a series of circumferentially spaced gusset plates 36.

To achieve rotary movement of the shaft 32, and consequently of the up-ender 29, I mount atop the plate 27 and on the rear surface of the carriage 17, a frame consisting of a pair of vertical plates 37 and an upper cross-member 39. Suspended from the cross-member 39 by brackets 22" and pin 24" for pivotal movement is a hydraulic ram 40, the piston rod 41 of which is pivotally and eccentrically connected to the shaft 32 through an arm 42 extending radially outwardly of the inner end of the shaft 32, as shown in Fig. 12.

On the forward face of the up-ender plate 30, I mount a pair of spaced, parallel, double-channelled or I beams 44 each providing a pair of opposed outwardly and inwardly facing channels 45 and 46, respectively.

A ram carrier 47 comprises a vertical plate 49 secured to which are rearwardly extending brackets 50 each pivotally carrying a rectangular self-aligning slide 51 disposed in the outwardly facing channels 45 for movement therein. The plate 49 of the ram carrier has mounted on its forward surface a pair of spaced, parallel channel or C beams 52, the channels 54 of which face each other, for a purpose to be described. One of these beams 52, the uppermost one as viewed in Figs. 10 and 11, has a pair of rearwardly extending brackets 55 to which are pivotally connected, as at 56, the piston rods 57 of a pair of hydraulic rams 59 whose cylinders are in turn pivotally mounted, as at 60, on the up-ender plate 30.

As I have already indicated, I provide a pallet carrier that is mounted for rotation with the up-ender and that is movable linearly in a line of direction parallel to the line of direction of linear movement of the ram carrier 47. I have chosen to illustrate the pallet carrier as a pair of forks 61 merging with a back plate 62, that is disposed parallel to the up-ender plate 30. As best shown in Fig. 10, this back plate has end brackets 64 opposite the inner channels 46 of I beams 44, and each such bracket 64 carries a pair of rectangular, self-aligning slides 65 disposed in the adjacent channel 46. The top of the back plate 62 has a pair of rearwardly extending brackets 66 each reinforced by a pair of gusset plates 67 between each pair of which is pivotally connected the piston rod 69 of a hydraulic ram. The cylinder 70 of each such ram is pivotally connected, as at 71, to the up-ender plate 30.

From the description thus far, it will be seen that the

carriage 17, and the up-ender 29, together with the ram carrier 47 may be moved vertically relatively to the uprights 16, by actuation of the hydraulic rams 21. Furthermore, the up-ender 29 can be rotated ninety degrees by extension of the piston rod 41 of the ram 40, since such movement of the rod 41 rotates the shaft 32 through the arm 42. Since the shaft 32 and the ram 40 are moved vertically along with the up-ender 29 by movement of the carriage 17, the up-ender may be rotated at any vertical position of the carriage.

It will further be seen that the guide members 44, together with the hydraulic rams 59 and 70 and the pallet carrier 61 are also carried by the up-ender so that they rotate together with the up-ender. In any rotated position of the up-ender, the ram carriage 47 may be moved linearly along the guide members 44 by actuation of the hydraulic rams 59. Similarly, the pallet carrier 61 may be moved linearly along the guide members 44 by actuation of the hydraulic rams 70 in any rotated position of the up-ender. I should invite attention here to the fact that all of the hydraulic rams referred to are of the double acting type in order to obtain positive reverse action; however, the rams 21 controlling elevation of the carriage may be single acting, if desired.

I have already alluded to the opposed C beams 52 mounted on the plate 49 of the ram carrier 47. At this point, I shall invite attention to the fact that these C beams are disposed in perpendicular relation to the guide members 44 for a purpose that will be made apparent later. The channels 54 of these beams confine self-aligning slides 72 that are pivotally carried by the opposed sides 74 of a yoke-like rear portion 75 of a ram supporting head 76. In order to move the head 76 linearly relatively to the plate 49 of the ram carrier, I provide a pair of double-acting hydraulic rams 77 the piston rods 79 of which are pivotally connected to the rear surface of the portion 75 of the head 76, as at 80 (Fig. 10), and the cylinders of which are pivotally connected to the plate 49, as at 81.

The dam supporting head 76 extends forwardly of the plate 49 and converges from the opposed sides 74, as viewed in Fig. 11 to support a shaft 82 on bearings 84 for rotation relatively to the head. One end of the shaft is reduced and screw threaded as at 85 to receive a retaining nut 86.

The ram 87 is supported from an arm 89 by a spacing beam 90, the ram 87 and the arm 89 extending from the beam 90 in parallel relation to one another. As shown in Fig. 14, arm 89 is supported adjacent one end by the shaft 82 for rotation therewith so that the ram 87 may rotate about the axis of this shaft. In order to effect this rotation, the head 76 carries a double-acting hydraulic ram 91 pivoted as at 92 to one side of the head and extending angularly thereof so that its piston rod 94 is pivoted as at 95 to a rotator 96. The rotator 96 is contoured to extend from the pivotal connection with the piston rod 94 outwardly of the head 76 through opening 97 provided for that purpose, whence it merges with the foremost portion of the arm 89.

It will be seen that in any position of the up-ender, while the ram carrier and the pallet carrier may move linearly in one line of direction, the ram 87 may also move linearly in a line of direction perpendicular to the line of direction of linear movement of the ram carrier and the pallet carrier. This movement of the ram 87 is accomplished through the head 76 by actuation of the hydraulic rams 77 to move the head along the channels 54 of the opposed C beams 52.

In operation, to lift a coil of tinplate, for example, the central cylindrical opening of which is horizontal, then bring a pallet into juxtaposed relation with one of the flat sides of the coil, rotate the coil and pallet together so that the central opening of the coil is vertical and the pallet is beneath the coil, and deposit the palleted coil on any flat surface, the truck of my present in-

vention is first driven to a position opposite a stack of pallets 192 as shown in Fig. 1. The pallet carrier, which I have chosen to illustrate as a pair of forks 61, may be elevated to the position suitable for inserting the forks into the uppermost pallet, this elevation being accomplished by actuation of the rams 21 to raise the entire coil handling structure mounted on the carriage 17. When the pallet carrier is raised to the proper height, the truck is driven forward and the pallet carrier is then raised slightly to lift the uppermost pallet from the stack. The up-ender is then rotated ninety degrees by actuation of the hydraulic ram 40 thereby rotating the ram carrier 47 and the pallet to the position shown in Fig. 2. In this position it will be seen that the beam 90 depends vertically from the arm 89 and that the ram 87 extends forwardly of the lowermost portion of the beam 90.

With the parts in this position, the truck is driven towards a roll of tinplate 194 while the supporting head 76 is raised or lowered by actuation of the hydraulic rams 77 to a position whereby the ram 87 will enter the cylindrical central opening 195 of the coil 194 as shown in Fig. 3.

After insertion of the ram 87 into the opening 195 of the coil, the entire carriage is then elevated by extension of the hydraulic rams 21 whereby the coil 194 is lifted from the supporting block 196 along with the pallet 192. When both the pallet and coil are freely supported by the apparatus of the present invention, the hydraulic ram 91 is then extended so as to rotate the coil ninety degrees about the vertical axis of the shaft 82 to bring one of the flat surfaces of the coil in opposed relation to the supporting face of the pallet 192, as best shown in Fig. 4.

In Fig. 5, I have illustrated a front elevational view of the truck showing the pallet brought into juxtaposed relation to one of the flat surfaces of the coil, this last operation being achieved by extension of the hydraulic rams 70 that control linear movement of the pallet carrier.

In order to bring the pallet and coil into position whereby they may be deposited with the pallet in supporting position relatively to the coil, the up-ender is rotated ninety degrees back to its original position as shown in Fig. 6. In this attitude, however, it will be seen that due to the previous elevation of the ram carrier, the rotation of the up-ender causes the extremity of the supporting head 76 to extend laterally outwardly beyond one side of the truck frame thereby extending the overall width of the truck. To eliminate this undesirable extension of the width of the truck, the hydraulic rams 59, controlling linear movement of the ram carriage relatively to the up-ender, are extended thereby moving the ram 87 upwardly until it is completely withdrawn from the central opening 195 of the coil, as shown in Fig. 7. The hydraulic rams 77 are then actuated to retract the piston rods 79 thereof, thereby shifting the supporting head 76 laterally to a position within the overall width of the frame of the truck as illustrated in Fig. 8. In this condition, the truck may be driven to any desired location and the palletized coil deposited upon a flat surface as shown in Fig. 9 by retracting the piston rods 57 of the hydraulic rams 21 thereby lowering the carriage 17.

From the foregoing description, it will be seen that I have contributed a novel coil handling truck that carries an up-ender for rotation about a horizontal axis relatively to the truck. It will also be seen that I contribute a coil lifting ram and a pallet carrier mounted for rotation with the up-ender, the ram also being mounted for rotation relative to the up-ender, and the up-ender itself being carried for vertical movement relatively to the truck. In my novel construction, the coil lifting ram is also movable linearly in a line of direction angular to the line of direction of linear movement of the ram carrier and pallet carrier. Further, the ram itself is also rotatable about an axis angular to the axis of the

rotation of the up-ender. The various operations possible by reason of my novel construction enables me to perform all of the functions required to up-end and palletize a coil with but a single machine.

5 I believe that the construction and operation of my novel coil handling truck will now be understood, and that the advantages of my invention will be fully appreciated by those persons skilled in the art.

I now claim:

10 1. In a truck of the class described, an upender mounted on said truck for rotation in a generally vertical plane, pallet supporting means carried by and rotatable with said upender, an article supporting ram carried by said upender spaced from said pallet supporting means and rotatable with said upender, and means mounting said article supporting ram for movement relative to said upender between a position in which said ram extends generally perpendicular to the plane of rotation of said upender and a position in which said ram extends generally parallel to said plane of rotation of said upender and towards said pallet supporting means whereby an article supported on said ram may be oriented relatively to a pallet carried by said pallet supporting means.

25 2. In a truck of the class described, an upender mounted on said truck for rotation in a generally vertical plane, pallet supporting means carried by and rotatable with said upender, an article supporting ram carried by said upender spaced from said pallet supporting means and rotatable with said upender, means mounting said article

30 supporting ram for movement relative to said upender between a position in which said ram extends generally perpendicular to the plane of rotation of said upender and a position in which said ram extends generally parallel to said plane of rotation of said upender and towards said pallet supporting means whereby an article supported on said ram may be oriented relatively to a pallet carried by said pallet supporting means, and means mounting said pallet supporting means and said article supporting ram on said upender for movement relatively toward and away

40 from each other.

3. In a truck of the class described, an upender mounted on said truck for rotation in a generally vertical plane, pallet supporting means carried by and rotatable with said upender, an article supporting ram carried by said upender spaced from said pallet supporting means and rotatable with said upender, means mounting said article supporting ram for movement relative to said upender between a position in which said ram extends generally perpendicular to the plane of rotation of said upender and a position in which said ram extends generally parallel to said plane of rotation of said upender and towards said pallet supporting means whereby an article supported on said ram may be oriented relatively to a pallet carried by said pallet supporting means, and means mounting said pallet supporting means and said article supporting ram on said upender for movement relatively toward and away

45 from each other.

4. In a truck of the class described, an upender mounted on said truck for rotation in a generally vertical plane, pallet supporting means carried by and rotatable with said upender, an article supporting ram carried by said upender spaced from said pallet supporting means and rotatable with said upender, means mounting said article supporting ram for movement relative to said upender between a position in which said ram extends generally perpendicular to the plane of rotation of said upender and a position in which said ram extends generally parallel to said plane of rotation of said upender and towards said pallet supporting means whereby an article supported on said ram may be oriented relatively to a pallet carried by said pallet supporting means, and means mounting said pallet supporting means on said upender for movement

50 towards and away from said article supporting ram.

5. In a truck of the class described, an upender mounted on said truck for rotation in a generally vertical plane, pallet supporting means carried by and rotatable with said upender, an article supporting ram carried by said upender spaced from said pallet supporting means and rotatable with said upender, means mounting said article supporting ram for movement relative to said upender between a position in which said ram extends generally perpendicular to the plane of rotation of said upender and a position in which said ram extends generally parallel to said plane of rotation of said upender and towards said pallet supporting means whereby an article supported on said ram may be oriented relatively to a pallet carried by said pallet supporting means, and means mounting said article supporting ram on said upender for movement

55 transversely of said pallet supporting means.

6. In a truck of the class described, an upender mounted on said truck for rotation in a generally vertical plane, pallet supporting means carried by and rotatable with said

60

65

70

75

upender, an article supporting ram carried by said upender spaced from said pallet supporting means and rotatable with said upender, means mounting said article supporting ram for movement relative to said upender between a position in which said ram extends generally perpendicular to the plane of rotation of said upender and a position in which said ram extends generally parallel to said plane of rotation of said upender and towards said pallet supporting means whereby an article supported on said ram may be oriented relatively to a pallet carried by said pallet supporting means, means mounting said pallet supporting means on said upender for movement

towards and away from said article supporting ram, and means mounting said article supporting ram for movement on said upender transversely of said pallet supporting means.
